UNITED STATES PATENT OFFICE.

ULRICH KORNSTEIN, OF NEW YORK, N. Y.

FOUNTAIN-PEN.

1,271,477.

Specification of Letters Patent. Patented July 2, 1918.

Application filed April 4, 1918. Serial No. 226,655.

To all whom it may concern:

Be it known that I, ULRICH KORNSTEIN, a citizen of the United States, and a resident of the city of New York, in the county of 5 New York and State of New York, have invented certain new and useful Improvements in Fountain-Pens, of which the following is a specification.

The present invention relates to self-filling fountain pens, and more particularly to that type which is equipped with compressible sacks of soft rubber or similar material, which sacks are adapted to store the ink and to fill themselves by suction after they 15 have been suitably compressed.

The main object of the invention is to provide a simple and effective means for distributing the compressing action substantially throughout the entire length of the 20 ink-sack, so as to effectively expel from the latter air when it is to be filled with ink.

Another object of the invention is to provide the fountain pen with means for rendering the level of the ink in the sack visible when the same drops below a normal 25 point, thereby indicating the necessity of refilling the pen.

A further object of the invention is to combine the sack compressing means with the ink level indicating means, so as to reduce the cost of production of the pen.

A still further object of the invention is to produce a fountain pen of the character described which can be manufactured on a 35 commercial scale, or in other words, one which is not so difficult to make as to be beyond a reasonable cost of such a contrivance.

With these and other objects in view, which will more fully appear as the nature 40 of the invention is better understood, the same consists in the combination, arrangement, and construction of parts hereinafter described, pointed out in the appended claims and illustrated in the accompanying drawings, it being understood that many 45 changes may be made in the size and proportion of the several parts and details of construction within the scope of the appended claims without departing from the spirit or 50 sacrificing any of the advantages of the invention.

One of the many possible embodiments of the invention is illustrated in the accompanying drawings, in which:—

55 Figure 1 is a plan view of a fountain pen constructed in accordance with the present

invention; Fig. 2 is a section taken on line 2—2 of Fig. 1, partly in elevation; Fig. 3 is a section taken on line 3—3 of Fig. 1, on a larger scale; Fig. 4 is a section similar to 60 the one shown in Fig. 3, with the elements in other positions; Fig. 5 is a plan view of the pen holder section and the ink-sack attached thereto; Fig. 6 is a section taken on line 6—6 of Fig. 5, on a larger scale; Fig. 65 7 is a plan view, partly in section, of the pen barrel; and Fig. 8 is a plan view, partly in section, of a protecting sleeve for the ink-sack.

In the drawings, the numeral 10 indicates 70 the barrel of a fountain pen, provided at one end with a holder 11, carrying a pen 12. To the inner end of the pen holder is fitted the open end of an ink-sack 13, that is, preferably, made of soft rubber and housed 75 by the barrel 10. Substantially throughout the length of the ink-sack extends a slot 14, in which is disposed a diaphanous strip 15, for instance of celluloid, that is cemented to or otherwise connected with the material of 80 the bag to present a liquid-tight receptacle. The inner end of the pen holder 11 is reduced in diameter, as clearly shown at 16, and over this reduced end is drawn a protecting sleeve 17 of metal or other suitable 85 material, said sleeve inclosing the sack 13, as clearly shown in Fig. 2 of the drawings.

The sleeve is provided near its outer end with an opening 18, preferably oblong, through which opening is accessible the strip 90 15 above referred to. With the opening 18 is adapted to register a preferably oblong opening 19 in the barrel 10, the said barrel being adapted to be rotated upon the pen holder in relation to the sleeve 17. 95

A cap 20 is provided for protecting, when the pen is not in use, its pen point, the cap being placed upon the closed end of the barrel when it is intended to use the pen in the well-known manner. 100

The operation of the device is as follows:—When it is intended to refill the pen, the barrel 10 is shifted upon the pen holder 11 until its opening 19 is brought into alignment with the opening 18 in the protecting 105 sleeve 17 (Figs. 1, 2 and 3). In this manner access can be had to the sack collapsing strip 15. By inserting now a finger into the registering openings 19 and 18 and forcing the sack collapsing strip 15 toward the opposite 110 portion of the barrel, the said ink-sack is collapsed substantially throughout its entire

length, whereby air is expelled therefrom. When now the pen is dipped into an ink-well and the ink-sack is permitted to distend, said sack will be filled with ink. After the 5 filling operation, the barrel 10 is turned upon the pen holder 11 until the openings 19 and 18 above mentioned are out of register (Fig. 4). In this manner the sleeve 17 protects the ink-sack against being compressed.

10 If it is intended to ascertain the level of the ink in the ink-sack, the diaphanous sack collapsing strip is exposed to view in the manner above described and the pen held with its closed end downward. If the level 15 of the ink in the sack then appears through the said strip within the opening 19 in the barrel, the pen should be refilled.

What I claim is:

1. A fountain pen, comprising a pen holding section, a barrel rotatably mounted thereon and provided with an opening near one of its ends, a compressible ink-sack attached to said pen holding section and disposed within said barrel, a diaphanous sack-collapsing strip forming part of said sack and extending substantially throughout the length thereof, and a sleeve secured to said pen holding section and interposed between said sack and said barrel, said sleeve being 30 provided with an opening in alinement with said collapsing strip and adapted to register with the opening in said barrel.

2. A fountain pen, comprising a pen hold-

ing section, a barrel rotatably mounted thereon and provided with an opening near one of its ends, a compressible ink-sack attached to said pen holding section and disposed within said barrel, a diaphanous rigid sack-collapsing strip forming part of said sack and extending substantially throughout the 40 length thereof, and a sleeve secured to said pen holding section and interposed between said sack and said barrel, said sleeve being provided with an opening in alinement with said collapsing strip and adapted to register 45 with the opening in said barrel.

3. A fountain pen, comprising a pen holding section, a barrel rotatably mounted thereon and provided with an opening near one of its ends, a compressible ink-sack attached to said pen holding section and disposed within said barrel, said sack being provided with a slot extending substantially throughout its length, a diaphanous sack collapsing strip covering said slot to produce a liquid-tight receptacle, and a sleeve secured to said pen holding section and interposed between said sack and said barrel, said sleeve being provided with an opening in alinement with said collapsing strip and adapted to register 60 with the opening in said barrel.

Signed at New York, in the county of New York and State of New York, this 2nd day of April, A. D. 1918.

ULRICH KORNSTEIN.
